UNITED STATES PATENT OFFICE

97,393

DESIGN FOR A KNEE PAD

Carl A. Judsen, Chicago, Ill., assignor to Judsen
Rubber Works, Inc., Chicago, Ill., a corporation
of Illinois

Application April 17, 1935, Serial No. 56,434

Term of patent 14 years

To all whom it may concern:

Be it known that I, Carl A. Judsen, a citizen of the United States and resident of Chicago, in the county of Cook and State of Illinois, have invented a new, original, and ornamental Design for a Knee Pad, of which the following is a specification, reference being had to the accompanying drawing, forming a part thereof.

Figure 1 is a view in perspective of a knee pad showing my new design;

Fig. 2 is a side elevational view of the same; and

Fig. 3 is a rear end view of the same.

The dominant feature of my invention comprises a one piece knee pad of substantially

cradle-shaped formation having a relatively high front wall connected to a relatively narrow rear wall by sloping side walls, the inclination of said side walls beginning at a point inwardly of said front wall and being relatively sharp at first and then sloping gradually towards the rear wall, and the bottom wall of said pad being provided with a plurality of transversely and longitudinally arranged rows of corrugations.

I claim:

The ornamental design for a knee pad, substantially as shown and described.

Signed at Chicago, in the county of Cook, and State of Illinois, this 4th day of April, 1935.

CARL A. JUDSEN
